UNITED STATES PATENT OFFICE

JORGEN BOYSEN, OF NEW YORK, N. Y.

MEANS FOR UTILIZING WATER POWER

Application filed May 14, 1931. Serial No. 537,333.

This invention relates to new and useful improvements in means that have for their purpose the utilization of the power of water, especially as such power is inherent to or 5 found in currents and streams of rivers and brooks.

The invention consists of an apparatus having substantially the circumference of a drum or cylinder, and may be made larger 10 and smaller according to the conditions at hand; at the same time any number of such apparatus may be employed, either to increase the power supply or to strengthen the power where the current is relatively weak. 15 The power thus produced may then in turn by suitable means of transmission be used for any desired purpose.

It is thought that while this invention may find a general application everywhere where 20 a river or brook is to be found, as a stream or current always is present in those, and inasmuch as by increasing the number of apparatus almost any desired amount of power may be produced, a great field of use for this 25 invention naturally would be found around in the country, where any small industry or farm at an insignificant cost may thus install their own power-plant.

The invention, i. e., the apparatus may 30 either be arranged in a specially constructed frame, when the latter naturally would support the end portions of the shaft or axle thereof, as hereinafter described, or the said apparatus may be lowered to, and rest upon, 35 the bottom of the river, in which case a system of gears in connection with an upright rod, a construction commonly known, would be resorted to for the transmission of the power from the said apparatus to the place of 40 actual utilization thereof.

As the construction of the apparatus is comparatively simple, the cost of manufacturing should be proportionately low.

With the above and other objects in view, 45 this invention consists of the novel features of construction, combination and arrangement of parts, hereinafter fully described, claimed and illustrated in the accompanying drawing forming part of this application, 50 and in which similar characters of reference

indicate corresponding parts in all views, and in which:

Figure 1 is an end elevational view of my invention; Figure 2 is a broken view on line 2-2 of Figure 1, partly in section; Figure 3 is in detail a perspective view of a segment, the end portion of one of the two frame-members constituting a segment being broken away; while Figure 4 is a top plan view 55 of my device.

Referring more particularly to the drawing, 10 indicates a segmental drum-member having a central shaft 11; to the latter is integrally and rigidly connected a plurality of, preferably five pairs or five double frame members, each pair of frame members constituting a segment; the arrangement of the said segments around the axle 11, may for the sake of clarity of understanding be imagined as five half-open books placed with 60 their backs against and grouped around the said shaft, as shown in Figure 1. The said cooperating frame members constituting the respective segments may thus be denominated 12, 12a; 13, 13a; 14, 14a; 15, 15a; and 16, 16a, 65 as seen in Figure 1.

The frame members 12, 13, 14, 15 and 16 have at their upper central portions disposed a short arm 17, the latter being made with a central opening, thereby serving as a support and engaging means for a rod 18, which has its opposite end rigidly embedded in the central shaft 11. To each of the said rods 18 are hingedly attached two congruent plate-members 19, 19. The said plate-members are 70 the creating means of power of the apparatus, as the said plates will cause the shaft 11 to turn as they open up as a result of the pressure exerted by the stream or current upon the said plates during their upward move of 75 80 the said plates during their cycle of travel. After the said plates have passed well above the center of the shaft 11, they start to close. However, in order to secure the said plates against bending 85 too far back, when in open position, a plurality of cross bars, in the present instance two bars 20, 20, are arranged upon one frame member of each segment, while on the other hand, two other cross bars 21, 21, more closely together, are arranged upon and forming 90 95 100

part of the opposite frame member of a segmental portion, in order to prevent the plates from closing entirely when they are moving downward at the opposite side of the stream 5 or current; the said plates will then in turn after having passed the lowest position gradually open up again to the pressure of the stream and thus keep up a rotating movement.

10 Around the segmental portions are rigidly fastened hoops 22 in order to lend strength to the structure.

If the said device is installed in a solid frame or a somewhat portal structure, as 15 shown in Figure 4, solid supports, as indicated at 23, may be provided for the shaft 11, and a system of transmission gears connected to the latter.

It is obvious that changes may be made in 20 the form, construction and arrangement of the several parts, as shown, within the scope of the appended claims, without departing from the spirit of the invention, and I do not therefore desire to limit myself to the construction and arrangement shown and described herein.

What I claim as new, and desire to secure by Letters Patent of the United States, is:

1. In a device of the class described, a cylindrically shaped rotating wheel, comprising a central hub, rectangular formed skeleton frame members arranged in pairs and being secured to the said hub, each pair of frame members having one of its members 30 formed with three cross bars arranged between the longitudinal sides of the said member, a pair of wing-formed plates pivotally mounted upon the center one of the three cross bars, the two outer cross bars serving 35 to stop the said plates, when in an extended position; the other one of each pair of frame members being formed with two cross bars between the longitudinal sides thereof, the latter cross bars being sufficiently close together to permit the said plates to nearly fold 40 together, when the latter are in an extreme position contrary to the extended one, during operation, and hoops encircling the said skeleton frame members.

50 2. In a device of the class described, a cylindrically shaped rotating wheel, comprising

ing a central hub, rectangular formed skeleton frame members arranged in pairs and being secured to the said hub, each pair of frame members having one of its members formed with two cross bars arranged between the longitudinal sides of the said member, a short arm formed with a central opening therein and being integrally attached to the outer longitudinal side of the said member, a rod having one end secured to the hub, and the other end mounted in the opening of the said short arm, a pair of wing-formed plates pivotally mounted upon the said rod; the other one of each pair of frame members being formed with two cross bars between the longitudinal sides thereof, the latter cross bars being arranged in a position near enough together to prevent the plates from folding upon each other during a closing movement of the latter, and hoops encircling the said skeleton frame members.

3. In a device of the class described, a cylindrically shaped rotary wheel, comprising a central hub, rectangular formed skeleton frame members arranged in pairs and being secured to the said hub, each pair of frame members having one of its members formed with two cross bars arranged between the longitudinal sides of the said member, a short arm formed with a central opening 90 therein and being integrally attached, at a right angle, to the outer longitudinal side of the said member and between the two cross bars, a rod having one end secured to the hub, and the other end mounted in the opening of the said short arm, a pair of wing-formed plates pivotally mounted upon the said rod; the other one of each pair of frame members being formed with two cross bars between the longitudinal sides thereof, the latter cross bars being arranged in a position near enough together to prevent the wing-formed plates from folding upon each other during a closing movement of the latter, and hoops surrounding the said skeleton frame members, substantially as shown and described.

Signed at New York city, in the county of New York and State of New York this 8th day of April, A. D. 1931.

JORGEN BOYSEN.
